(57) **CLAIM**

The ornamental design for an LED face roller, as shown and described.

DESCRIPTION

FIG. 1 is a front perspective view of an LED face roller according to the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the equal-length broken lines depict unclaimed portions of the LED face roller that form no part of the claimed design. The dash-dot-dash broken lines define the boundaries of the claim. All broken lines form no part of the claimed design.

1 Claim, 3 Drawing Sheets
